UNITED STATES PATENT OFFICE.

CHARLE OLSON, OF LAFAYETTE, MINNESOTA.

DISHWASHING MACHINE.

1,421,543.

Specification of Letters Patent. Patented July 4, 1922.

Application filed June 5, 1920. Serial No. 386,694.

To all whom it may concern:

Be it known that I, CHARLE OLSON, a citizen of the United States, residing at Lafayette, in the county of Nicollet and

5 State of Minnesota, have invented certain new and useful Improvements in Dishwashing Machines, of which the following is a specification, reference being had to the accompanying drawings.

10 This invention relates to an improved dish washing machine, and an object is to provide an apparatus of this kind, wherein the dishes are received at one end to be washed or thoroughly cleansed and taken from the other end of the machine, and then again passed through the machine to be rinsed, in combination with a suitable rack at one end of the frame of the machine to support the dishes and permit them to be drained.

15 Another object is to provide an apparatus of this kind wherein means are operatively mounted in the frame of the machine for conveying the dishes under the rotary brushes in order to be washed and rinsed.

20 Still another object embodies a machine of this kind including a rotary fountain brush for washing cups and the like.

25 Additionally the invention aims to provide an apparatus of this kind wherein means is afforded for conveying water into the rotary brushes which are used for washing the dishes, so as to thoroughly cleanse them as they pass under the brushes.

30 Furthermore it is the aim to provide a tank for the reception of water under pressure so that it will pass into the brushes with sufficient force to spray from the brushes upon the dishes.

35 Furthermore, the invention also provides a dish draining rack with means for holding the dishes on their edges so that they will properly drain, the top of the base being inclined and perforated so that the water will drain into the chamber in the base.

40 While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features

and combination of parts, as will be hereinafter set forth, shown in the drawings and claimed.

In the drawings:

Figure 1 is a view in side elevation showing the gearing for operating the various washing rollers in dotted lines and illustrating the hand crank for turning the rollers,

Figure 2 is a vertical sectional view on line 2-2 of Figure 1, more clearly showing the gear connection and the means for conveying the water from the tank to one of the washing rollers or brushes,

Figure 3 is a sectional view on line 3-3 of Figure 2, showing the interior construction of the dish washing apparatus illustrating the perforated water receiving rollers which have brush bristles and also showing the cup washing rotary brush in section and illustrating a conveyor for conveying the dishes back and forth through the machine,

Figure 4 is a view in side elevation of the opposite side of the dish washing apparatus, showing the hose connections to the rotary cylinders or brushes and to the cup washing brush; and

Figure 5 is an enlarged detail sectional view of a hose coupling connection with one of the rotary brush cylinders.

Referring to the drawings, 1 designates a housing or superstructure and 2 denotes a base, which supports the housing or superstructure and is provided with a chamber or compartment 3 for the reception of the refuse water. The base 2 is mounted upon suitable supporting legs 4, there being a drain outlet opening at the center of the bottom of the chamber, and communicatively connected with this opening 5 is a drain pipe 6 provided with a valve 7. The top 9 of the chamber 3 is inclined and is perforated as at 8 to permit the refuse water to drain into the chamber. One end of the top 9 of the chamber is extended and has transverse ribs 10 to be engaged by the edges of the dishes when they are supported in inclined positions and to prevent them from slipping. The extension of the top 9 of the chamber has perforations 11 to permit the water draining from the dishes to pass into the chamber 3. A suitable rack 12 is secured to the sides of the base as at 13 and arches over the extension of the top of the

chamber. This extension has a marginal flange to retain the water on the top so that it will drain into the chamber. The extension is slightly inclined as shown, to facilitate the draining of the water. A clamping rack 14 is pivotally mounted at 15 on the sides of the base of the housing and having coil springs 16 to hold the clamping rack against the dishes, which are arranged on their edges on the ribbed extension of the top of the chamber to prevent displacement of the dishes, and to hold them so that they can readily drain.

The housing includes the sides 17, which are supported on the bottom of the base, and support the various washing brush cylinders. Mounted in bearings on the sides 17 of the housing are rollers 18, 19, 20, 21, 22 and 23 about which a rubber or other suitable conveying belt 24 travels. The belt 24 passes over the roller 18 under the roller 20, over the roller 22 and then over the roller 19 and the roller 21, and thence over the roller 23 and back to the roller 18. This belt is corrugated as shown at 25, and travels in the direction of the arrow *a* so that when the dishes are arranged one at a time flatwise on the belt they will be carried in the direction of the arrow *a* and then move in an inclined direction upwardly where they can be extracted. As the dishes are traveling with the belt they are thoroughly washed by the brush bristles of the rotary brush cylinders 26, which are mounted in bearings of the sides 17 of the housing.

These rotary brush bristles rotate toward each other and downwardly as indicated by the arrows *b*. The bristles 27 of the brushes are long enough so as to sweep over the dishes as they pass thereunder.

Mounted in bearings of the sides of the frame above the rotary brush cylinders are rollers 28 over which a rubber or other suitable belt 29 travels. This belt 29 is endless and has its outer surface corrugated similar to the belt 24. The dishes as they are washed by the rotary brush bristles are placed on the belt 29 and returned to the end of the machine where they were first inserted. As the dishes are carried by the belt 29 they are further brushed, and are rinsed by the water from the spray or sprinkler pipe 30 which extends transversely from one side of the housing to the other. The brushes 31 and 32 for additionally brushing the dishes as they are carried by the belt 29, are mounted in bearings of the sides 17 of the frame of the machine.

The brush cylinders are hollow and have perforations 33 so that water can spray therefrom. One end of each of the brush cylinders is provided with a reduced extension 34 to which a coupling pipe 35 is connected by means of the nipple 36. This nipple has a swivel connection with the re-

duced extension, there being a washer 37 to prevent excessive leakage of the water. Mounted upon the frame 1 is a water receiving tank or reservoir 38, into which water under pressure may enter by means of the supply pipe 39. Connected to an outlet opening 40 of the tank or reservoir is a valve 41 which connects to an auxiliary casing 42 having a chamber 43. The chamber 43 is provided with outlet openings 44 to which hose 45 and 46 are connected. These hose 45 and 46 are in turn connected to the pipe couplings 35 so as to convey water from the reservoir into the hollow rotary brush cylinders. A pipe 47 also extends from the chamber 43 and is connected at 48 to the supply pipe 30 which is disposed transversely of the upper part of the frame in a position substantially over the central portion of the conveyor belt 29. It will be noted that by opening or closing the valve 41 the water into the rotary brush cylinders 26 and the spray pipe 30 may be controlled.

The rotary brush cylinders at certain of their end portions are provided with openings 49 having closures 50 which when open, soap shavings may be inserted so that when the water enters the cylinders and then sprayed therefrom, it is fit to remove the grease from the dishes.

Mounted upon one of the extensions 34 of one of the brush cylinders is a bevel gear 51, which meshes with a bevel gear 52 on a tubular shaft 53, which is mounted in bearings 54 of one side of the housing. A tubular coupler 55 is mounted in a bearing 56 of one side of the housing, and telescopically fits into the shaft 53 so as to carry water thereinto. A short pipe 57 is connected to the tank or reservoir and has a valve 58. A hose or tube 59 connects the valve 58 and the coupling 55 so that when the valve 58 is open water will pass from the tank or reservoir under pressure through the tubular shaft 53 and thence to the cup washing brush 60. This cup washing brush comprises a semi-spherical hollow head 61, which is threaded or otherwise fastened at 62 to the tubular shaft 53. This brush head is provided with radially projecting brush bristles 63 and is also supplied with perforations 64. The brush bristles act to remove the dirt from the interior of the cups or other hollow dishes, while the water spraying through the perforations act to wash the dirt and the like from the cups and then into the chamber of the base. It will be noted that other forms of dish washing fountain brush may be attached to the tubular shaft 53, in order to wash various shapes of dishes instead of passing them through the machine on the belt.

Gears 65 and 66 are mounted upon the reduced extensions of the other ends of the rotary brush cylinders, and are intermeshed

so that the brush cylinders may rotate toward each other and downwardly as indicated by the arrows in Figure 3. One of the rollers 28 of the belt 29 carries a sprocket 67, about which a chain 68 travels. This chain 68 in turn engages a sprocket 69 on the reduced extension of the rotary brush cylinder which carries the gear 65. The rotary brush cylinder which carries the gear 66 is rotated by hand, there being a crank 70 connected to one end of the rotary brush cylinder in order to impart movement thereto. The rotary brush cylinder which carries the gear 66 has a sprocket 71 which is engaged by a sprocket chain 72, which passes about a sprocket 73 carried by one end of the rotary brush 32. The rotary brush 31 on one end carries a gear 74, which meshes with a gear 75 on the end of the brush 32. It will be noted that power is transmitted from the rotary brush cylinder having the gear 66 to the gear 65 and thence to the other fountain rotary brush cylinder, then to the conveyor 29 and from the rotary fountain brush cylinder carrying the gear 66 to the brush 32 by means of the chain 72.

A gear 76 is mounted upon one end of the roller 18 and is in mesh with the gear 65 so that power may be transmitted from the gear 65 to the conveyor 24. In other words, it will be noted that by manipulating the rotary brush cylinder carrying the gear 66, the remaining moving parts of the apparatus are capable of movement so as to perform the function of washing and rinsing the dishes and carrying the dishes through the machine. One end of the base of the frame of the machine has an extension board 77 on which the dishes to be washed may be placed. The dishes are passed one at a time into the opening 78 of one end of the machine upon the conveyor or belt 24 and then they are removed from the other end of the machine and placed upon the conveyor 29 so that they can be rinsed and further washed by passing under the brushes 31 and 32 and the sprinkling pipe 30. The dishes are removed from the upper part of the housing of the machine through the opening 79 and are placed on the drain rack as shown in the sectional view of Figure 3. The upwardly and inwardly extending part of the conveyor belt 24 is adjacent the extension flange 80. One side of the casing 1 at a point immediately above the extension flange 80, an opening 81 is formed, so as to permit the removal of the dishes, and the insertion of the dishes between the conveyor 29 and the brushes 31 and 32.

The conveying belts 24 and 29 may be either endless or provided with buckles 24^a and 29^a so that the belts can be easily taken off if desired. Furthermore, if desired, the crank 70 may be dispensed with if desired, and any suitable power belted to the shaft

so that the machine may be operated mechanically instead of manually.

The invention having been set forth, what is claimed as new and useful is:

1. In an apparatus for the purpose indicated, a base, a housing supported thereon, rotary fountain dish washing brushes mounted on the housing, opposite walls of the housing having dish inlet and outlet openings, an endless conveyor extending from the outlet opening horizontally over two rollers below the washing brushes and outlet opening, then downwardly and around two rollers beneath said first named rollers, then upwardly, passing said horizontal portion and over a roller at the outlet opening, whereby the dishes may be conveyed under the brushes, and then upwardly toward the outlet opening through which the dishes pass when removed from the conveyor.

2. In a washing apparatus for the purpose indicated, a base, a superstructure mounted on the base and provided with opposite inlet and outlet openings, a conveyor mounted in the housing and operable to convey dishes from the inlet opening to the outlet opening, rotary fountain brushes arranged immediately above and adjacent the conveyor, a spray pipe above the conveyor, a water reservoir on the housing, means connecting the reservoir and the fountain rotary brushes, means connecting the reservoir to the spray pipe, and means common to the respective connecting means for controlling the supply of water to the fountain brushes and the spray pipe.

3. In a washing apparatus for the purpose indicated, a base, a housing supported on the base and having a water reservoir, dish washing means including rotary fountain brushes mounted in the housing, a spray pipe above the dish washing means, an auxiliary chamber having a valve controlled connection with the reservoir, and means connecting the auxiliary chamber and the respective rotary brushes and the spray pipe.

4. In a washing apparatus for the purpose indicated, a base, a housing mounted on the base and provided with a water reservoir, an auxiliary chamber, a pipe connecting said chamber and said reservoir, dish washing means including rotary fountain brushes mounted in the housing, a spray pipe mounted in the housing above the brushes, means connecting the brushes and the chamber, means connecting the chamber and the spray pipe, and a valve carried by the pipe connecting the chamber and the reservoir, whereby the supply of water may be controlled to the brushes and spray pipe simultaneously.

In testimony whereof I hereunto affix my signature.

CHARLE OLSON.
